UNITED STATES PATENT OFFICE.

WILLIAM FORD McCLELLAN, OF BROOKLYN, NEW YORK.

SHOE-TREE.

1,142,595.

Specification of Letters Patent.

Patented June 8, 1915.

Application filed August 6, 1914. Serial No. 855,451.

To all whom it may concern:

Be it known that I, WILLIAM FORD McCLELLAN, a citizen of the United States, residing at Brooklyn, in the county of Kings and State of New York, have invented certain new and useful Improvements in Shoe-Trees; and I do declare the following to be a full, clear, and exact description of the invention, such as will enable others skilled 10 in the art to which it appertains to make and use the same.

My invention relates to improvements in shoe trees and has for its main object to improve upon devices of this character to such 15 an extent as to provide an extremely simple yet highly efficient tree which may be inexpensively constructed.

In carrying out the above end, I provide a pair of slidably engaged overlapped strips, 20 toe and heel engaging members carried by said strips and a locking device whereby said strips may be locked in any one of their adjusted positions.

A further object of the invention becomes 25 to construct the locking device of a single piece of resilient wire and to so form the same as to allow the strips to slide one upon the other in one direction but to prevent movement thereof in the opposite direction. 30 A further object is to so form the opposite ends of the strips as to provide efficient guides and means for attachment of the heel and toe engaging members.

Yet another object is to provide, in connection with the above mentioned features, 35 an inclined and curved resilient plate designed to support the vamp of the shoe in proper position.

With the above and minor objects in view, 40 the invention resides in certain novel features of construction and combination herein described and claimed and shown in the drawings wherein—

Figure 1 is a side elevation of the device 45 constructed in accordance with my invention; Fig. 2 is a top plan view thereof; Fig. 3 is a transverse section taken on the line 3—3 of Fig. 1; and Fig. 4 is a detail perspective view of the locking device.

In the accompanying illustration, I have 50 shown my invention as including, in general, front and rear strips 1 and 2 which are overlapped and slidably engaged, a toe engaging member 3 carried by the strip 1, a

heel engaging member 4 carried by the strip 55 2, and a locking device 5 for locking the strips 1 and 2 in adjusted position.

The forward end of the strip 1 is turned upwardly to provide an attaching ear or foot 6 through which fastening screws 7 60 are passed into the rear end of the toe engaging member 3, said member being here shown in the form of a suitably shaped block.

Interposed between the ear 6 and the member 3, is an upright attaching shank 8 which is formed on the lower end of an upwardly and rearwardly inclining vamp supporting plate 9, said plate being widened at its upper end as indicated at 10 and being curved a 70 proper extent to allow the same to snugly engage the under side of said vamp. This plate 9 is formed of resilient material in order that it may yield to conform to shoes having either high or low insteps. 75

The rear end of the strip 1 is formed into a transverse bearing loop 11 which overlies the strip 2 and which receives a link 12 which embraces said strip 2, the forward end of said last mentioned strip being formed 80 into a transverse loop 13 which underlies the strip 1 and which receives a link 14 embracing said strip 1. By this means, the two members 1 and 2 are slidably connected. The rear end of the strip 2 is here shown as 85 being bent upwardly to form an attaching ear or foot 6' through which screws 7' are passed into the forward side of the heel engaging member 4, the latter being here shown in the form of a substantially semi-cylindrical block. Said strip 2 is likewise 90 provided with a longitudinal series of openings 15 the walls of which constitute stops for coaction with the locking device 5 in a manner to be set forth. 95

The device 5 comprises a transverse rock shaft 16 which is mounted in the loop 11 adjacent the link 12, an inwardly extending arm 17 formed integrally with one end of said shaft and having a depending nose 18 100 on its free end, said nose being adapted for engagement with said openings 15, an upright lever 19 formed integrally with and rising from the opposite end of said rock shaft 16, and a substantially upright spring member 20 having its upper end formed integrally with the upper end of the lever 19, its lower end being provided with a later-

ally extended foot 21 which contacts with the upper surface of the strip 1.

As clearly seen in the drawings, the arm 17 is shown as substantially L-shape 5 although this formation need not be followed too strictly since a rectilinear arm would operate to equal advantage for constituting a detent coöperating with the openings 15.

10 With the parts as above described, the strips 1 and 2 may be pulled outwardly in opposite directions during which movement the nose 18 will disengage certain of the openings 15 and engage other openings 15 thereby locking the device in any one of its adjusted positions, it being understood that the action of the spring arm 20 normally retains said nose in yielding engagement with the upper surface of the strip 2 or with the 20 walls of said openings as the case may be. When the parts stand in locked position, as seen in full lines in Fig. 1, it will be noted that the nose 18 inclines to an extent great enough to allow the same to be retracted 25 against the tension of the spring arm 20 when the strips 1 and 2 are moved outwardly but the said nose will more closely engage the walls of said openings when said strips are forced toward each other, provided the lever 30 19 be not rocked around its pivot 16. When said lever is rocked, however, the spring arm 20 assumes the position shown in dotted lines in Fig. 1 and the arm 17 and nose 18 are raised to the position likewise seen in dotted 35 lines in said figure thereby allowing the two strips 1 and 2 to be adjusted one toward the other.

From the foregoing description taken in connection with the accompanying drawings, it will be seen that I have produced an extremely simple construction for carrying out the objects of the invention, that the locking device 5 may be constructed of a single piece of wire and therefore inexpensively manufactured, that the construction of the strips 1 and 2 is extremely simple for gaining the functions for which said strips are designed and that the provision of the yielding plate 9 will effectually support the vamp of a shoe as hereinbefore set forth.

Having thus described my invention, what I claim as new and desire to secure by Letters Patent is:

55 1. A shoe tree comprising a pair of overlapped slidably engaged strips, a plurality of longitudinally spaced stops on one strip, and a pivotally mounted spring pressed detent on the other strip and adapted to engage said stops.

2. A shoe tree comprising a pair of overlapped slidably engaged strips, a plurality of stops on one strip, a transverse bearing on the other strip, a transverse rock shaft in 60 said bearing, a detent projecting rigidly

from one end of said rock shaft and adapted to engage said stops, an operating lever rigidly connected to the other end of the shaft and a spring for normally engaging said detent with one of said stops.

3. A shoe tree comprising a pair of overlapped slidably engaged strips, a plurality of stops on one strip, a bearing on the other strip, a transverse rock shaft in said bearing, a detent projecting rigidly from one 70 end of said shaft and adapted to engage said stops, an operating lever rising from the other end of the shaft and a spring attached to the lever and bearing against one of said strips whereby to normally force 75 said detent into engagement with one of said stops.

4. A shoe tree comprising a pair of overlapped slidably engaged strips, a plurality of stops on one strip, a bearing on the other strip, a transverse shaft in said bearing, a 80 detent projecting rigidly from one end of said shaft and adapted to engage said stops, an operating lever rising from the other end of the shaft and a substantially upright 85 spring formed integrally with the upper end of the lever and bearing at its lower end against one of said strips.

5. In a shoe tree, the combination with a pair of slidably engaged overlapped strips, a bearing on the inner end of one strip and a plurality of stops on the adjacent portion of the other strip, of a locking device comprising a transverse shaft mounted in said bearing, an inwardly extending arm on one 95 end of said shaft and having a depending nose adapted to engage said stops, a lever formed integrally with and rising from the other end of said shaft, and a substantially upright spring arm formed integrally with 100 the lever and having a foot contacting with one of said strips.

6. A shoe tree comprising a pair of flat overlapped slidably engaged strips having 110 their outer ends bent upwardly to form attaching feet, toe and heel engaging blocks contacting with said feet, fastening elements passing through said feet and into said blocks and a locking device for securing said strips against movement.

7. In a shoe tree, a toe engaging block shaped to conform to the shape of the toe of a shoe, an inclined plate secured at its front end to said block and extending rearwardly therefrom, said plate being formed of resilient material, and means whereby said block may be forced into the toe of a shoe.

8. In a shoe tree, a heel engaging member, a strip forward of said heel engaging member and slidably connected therewith, said strip having its forward end turned upwardly to provide an attaching ear, a toe engaging block spaced forwardly from said ear, an upwardly and rearwardly inclining curved resilient plate having its forward 125 130

end located between said ear and said block, and fastening elements passing through said ear, the forward end of said resilient plate and into said block, the upper rear end of 5 said plate being increased in width for the purpose set forth.

In testimony whereof I have hereunto set

my hand in presence of two subscribing witnesses.

WILLIAM FORD McCLELLAN.
